UNITED STATES PATENT OFFICE.

EDWARD E. ROGERS, OF NEW YORK, N. Y.

SHARPENING DEVICE.

1,426,911.

Specification of Letters Patent. Patented Aug. 22, 1922.

Application filed February 21, 1922. Serial No. 538,322.

To all whom it may concern:

Be it known that I, EDWARD E. ROGERS, a citizen of the United States, and resident of the city of New York, borough of Bronx, county of Bronx, and State of New York, have invented a new and Improved Sharpening Device, of which the following is a full, clear, and exact description.

My invention relates to a sharpening device and aims to provide certain new and useful improvements in connection with a machine of this character.

It is an object of this invention to provide a device of the type stated which shall be extremely simple in construction and capable of being placed upon the market at a nominal figure, aside from the fact that the same shall be capable of being utilized by an operation of the greatest simplicity.

20 A further object of this invention is that of constructing a sharpening device by means of which knives and similar cutting elements may quickly have an edge formed upon their blade, it being noted however that this edge is formed by a manual operation and without the aid of any mechanical or electrical operating members.

Still another object of this invention is that of providing a sharpening device of the type stated in which the position and subsequent actuation of the blade to be sharpened will result in the operation of the parts of the device so that the operation of the latter is reduced to the simplest terms possible.

35 A still further object of this invention is that of providing a sharpening device embodying the aforementioned qualifications, and which in addition to being capable of placing a cutting edge upon a knife will also lend itself to the forming of a proper cutting edge upon a pair of shears.

Still further objects of this invention will become apparent in the annexed specification taken in connection with the drawings which latter illustrate one practical embodiment of the same, and in which;

Figure 1 is a sectional side view of a sharpening device.

Figure 2 is a plan view thereof, both of these figures showing my device while the parts are being actuated to sharpen a knife.

Figure 3 is a plan view similar to Figure 2 but showing a portion of the cover broken away to disclose the underlying construction and also showing a pair of shears applied to the said sharpening device, and

Figure 4 is an end view thereof.

It will be seen in these views that the reference numeral 5 indicates the base of the device to which spaced side walls 6 are secured, the latter supporting adjacent their upper edges, platforms 7 having their adjacent edges spaced and preferably provided with guide flanges 8.

Positioned within the enclosure thus provided are shafts 9 which are angularly disposed with respect to the side walls and the base, and have their axis arranged substantially at right angles with respect to each other; it being noted that their lower ends are rotatably supported in line with each other, as has been shown in Figures 2 and 4. A pair of drums 10 are affixed one to each of the shafts and supported thereby, these drums being spaced from each other as in Figure 2, and having their contact faces disposed at that angle to the vertical corresponding to the angle at which a cutting edge should be formed with respect to the body of the blade.

Thus as in Figures 1, 2 and 4 it will be seen that a blade 11 may be brought to extend into the slot formed by the spacing of the platforms 7, and this blade is brought to a position at which its body is supported by the contact established between its cutting edge and the perforations of the drums 10. It will be noted in this connection that incident to the fact that the faces of the drums are disposed at that angle to the vertical at which the cutting edge should be formed with respect to the body of the blade that these faces will engage the cutting edge of the blade 11 properly. Also it will be obvious that the blade may now be drawn through the body of the sharpening device and when this action is resorted to a rolling and grinding contact will be established between the cutting edge of the same and the faces of the abrasive drums so that upon this operation being repeated a number of times the blade will be properly sharpened.

Furthermore, as has been clearly indicated one of the side walls 6 is preferably formed with a slot 12, and one of the end edges of the platform 7 secured to this side wall is extended downwardly as at 13 to provide a guide. Thus it will be obvious that a shear may have one of its blades brought to extend through the slot 12, as in Figure 3, and it will be seen that the extended portion 13 in this instance, acts as a guide for

the shear to steady the same when its cutting edge is in contact with the outermost of the abrasive drums 10. Also due to the angular disposition of this drum with respect to the 5 side wall and slot, and consequently with respect to the shear blade extending through the slot, it will be obvious that a proper contact will be established between the edge of the blade and the drum thus insuring an efficient 10 sharpening of the former upon the same being reciprocated within the slot 12, and along the extended portion 13.

Thus all of the objects of this invention have been accomplished, and it will further 15 be appreciated that numerous modifications of structure might readily be resorted to without in the least departing from the scope of my claims; which are—

1. A grinding device including a base, a 20 platform extending above and in spaced relationship to said base, said platform being formed with a slot, guide flanges formed adjacent to said slot, shafts extending between said platform and said base, said shafts being 25 rotatably mounted and disposed at an angle to each other and to the said slot and

base, and abrasive drums secured to said shafts and having their working faces extending substantially parallel to the same.

2. A grinding device including a base, 30 side walls extending from said base, a platform secured to said side walls and in spaced relationship to said base, grinding members disposed between said platform and base, said platform being formed with a slot at a 35 point above said grinding members, one of said side walls being formed with a slot in line with one of said grinding members.

3. A grinding device including a base, 40 side walls extending from said base, a platform secured to said side walls and in spaced relationship to said base, grinding members disposed between said platform and base, said platform being formed with a slot at a point above said grinding members, one of 45 said side walls being formed with a slot in line with one of said grinding members, and an outer wall forming a part of said device and in line with one of the edges of said last named slot, said wall being adapted to act 50 as a guide.

EDWARD E. ROGERS.
